UNITED STATES PATENT OFFICE

107,568

DESIGN FOR A MAILING NOVELTY

Chester E. Walker, Branson, Mo.

Application September 13, 1937, Serial No. 71,578

Term of patent 7 years

To all whom it may concern:

Be it known that I, Chester E. Walker, a citizen of the United States, residing at Branson, in the county of Taney and State of Missouri, have invented a new, original, and ornamental Design for a Mailing Novelty, of which the following is a specification, reference being had to the accompanying drawing, forming a part thereof.

Fig. 1 is a side elevational view of a mailing novelty showing my design.

Fig. 2 is a top view.

I claim:

The ornamental design for a mailing novelty as shown.

CHESTER E. WALKER.
